Primary Examiner—Stella Reid*Attorney, Agent, or Firm*—Timmons & Kelly; H. Dennis Kelly[57] **CLAIM**

The ornamental design for a slip-on bottle holder with handles, as shown and described.

DESCRIPTION

FIG. 1 is a perspective view of a slip-on bottle holder with handles showing my new design;

FIG. 2 is a side elevation thereof, the opposite side being identical thereto;

FIG. 3 is a top plan view, the bottom view being a mirror image thereof;

FIG. 4 is a front elevation thereof; and,

FIG. 5 is a rear elevation thereof.

FIG. 1

FIG. 3

FIG. 4

FIG. 2

FIG. 5
